(57) **CLAIM**

The ornamental design for a protection cushion, as shown and described.

DESCRIPTION

FIG. 1 is a top, front, and left side axonometric view of a protection cushion, showing our new design;

FIG. 2 is a top, front, and right side axonometric view thereof;

FIG. 3 is a bottom, front, and left side axonometric view thereof;

FIG. 4 is a bottom, rear, and right side axonometric view thereof;

FIG. 5 is a bottom, rear, and left side axonometric view thereof;

FIG. 6 is a front view thereof;

FIG. 7 is a rear view thereof;

FIG. 8 is a left side view thereof;

FIG. 9 is a right side view thereof;

FIG. 10 is a top view thereof; and,

FIG. 11 is a bottom view thereof.

The broken lines seen adjacent to the shaded surfaces and within those areas depict portions of the protection cushion that form no part of the claimed design. All other broken lines seen in the drawings depict unclaimed environmental subject matter only and form no part of the claim.

1 Claim, 11 Drawing Sheets
